AIR CONDITIONING DEVICE

Filed Aug. 3, 1931

UNITED STATES PATENT OFFICE

JOHN H. KITCHEN, OF KANSAS CITY, MISSOURI, AND FRANCIS A. KITCHEN, OF CLEVELAND, OHIO, ASSIGNORS TO MABEL L. KITCHEN, OF KANSAS CITY, MISSOURI, AND FRANCIS A. KITCHEN, OF CLEVELAND, OHIO

AIR CONDITIONING DEVICE

Application filed August 3, 1931. Serial No. 554,746.

This invention relates to improvements in an air conditioning device and refers more particularly to a cooling unit for conditioning air whereby the air is cooled by passing it through cold water sprays, the water being cooled by a refrigerant such as ice. The invention also has reference to a device for melting the ice rapidly and at a relatively constant rate.

10 A further novelty of the invention lies in an arrangement for cooling the water by means of contact with an extended metal surface platform which has a high degree of conductivity so that the cooling effect of the

15 ice is passed to the reservoir or pool of water maintained at the bottom of the ice at a very rapid rate.

A further novelty of the invention lies in the insulating of the extended surface platform so that the heat conducted to the ice will be confined in a great measure to the pool of water maintained below the ice and but a small amount of heat lost by conduction or convection from the shell or casing

25 of the device with the outside air.

A further feature of novelty is the arrangement of the parts of the device to secure a reduction in temperature of the water contacting the extended surface platform by controlling the path of the flow of water around the extended metal surface.

The application is a continuation in part of previous applications, filed in the name of Francis A. Kitchen, Serial Numbers, 500,195, dated December 5, 1930 and 508,132 dated January 12, 1931.

Fig. 1 is a sectional view of the air conditioning device.

Fig. 2 is a view taken along the lines 2—2 in Fig. 1 in the direction of the arrows.

Fig. 3 is a modified type of platform for supporting the refrigerant.

Fig. 4 is a second modification showing a different type of structural features for the refrigerant platform.

Referring to the drawing, the casing or enclosure 1, heavily insulated as shown at 2, is divided by a partition 3 into a refrigerant compartment 4 and a spray compartment or air conditioning compartment 5. The air

conditioning compartment is divided by a partition 6 which extends only a portion of the way to the bottom of the compartment. In the partition 3 between the refrigerant compartment 4 and the air compartment 5 is a closure or door 7 by means of which access is obtained to the piping or sprays in the spray compartment. An aperture 8 in the lower part of the partition 3 is placed at one end of the platform so that water may flow uniformly over or around the platform and through its longest side increasing the chilling of the water and serving to maintain the liquid level of the pool of water 9 the same in both of the compartments. An overflow line 10 controls the water level. It is to be noted that this overflow pipe is at the warmest place of the unit. This prevents a waste of chilled water and renders the device more efficient.

A refrigerant such as ice, as shown at 11, is placed in the refrigerating compartment 4 through a door in the casing not shown. Air to be conditioned is introduced through the duct 12 passing downwardly through the compartment 5 to the bottom of the partition 6 and then upwardly in the direction of the arrows and out through the duct 13 which is connected to the suction side of an exhaust fan or blower 14 by means of which it is distributed through a discharge pipe 14 to any desired location. In its passage through the compartment 5 the air is subjected to the cooling effect of water at a relatively low temperature, sprayed into the compartment by means of nozzles 16 and 17. In one portion of the air conditioning compartment the air passes substantially in a concurrent direction with the particles of moisture or water from the spray and in the other half of the compartment in a relatively countercurrent direction with the droplets of water from the spray.

The spray nozzles 16 and 17 are supplied with the cooling water from the reservoir 9 by means of a circulating pump 18 driven by any suitable source of power such as the motor shown at 19. The suction side of the pump 18 is connected by a pipe 20 with the reservoir of water maintained in the refrigerating compartment 4. An auxiliary suc-

- tion pipe 21 communicates with the pool of liquid maintained in the spray compartment. In the pipe 21 is interposed a valve 22. By means of this valve the proportioning of the water from the pool in the refrigerating chamber to the pool in the spray chamber is accomplished. If a single valve is insufficient, a second valve may be interposed in the line 20 between the reservoir and the point where the pipe 21 joins the pipe 20 so that the water taken from the refrigerating compartment may also be limited and controlled.
- The water is discharged from the pump 18 through a pipe 23 which terminates in a vertical line 24 to which secondary lines 25 and 26 are connected, the latter lines terminating in the spray nozzles 16 and 17. The pipe 27 is also connected into the discharge line 23 from the pump, which line terminates in a spray 28, positioned in the refrigerating chamber. In the pipe 27 is interposed a valve 29. By means of the line 27, a portion of the water circulated for air conditioning is sprayed over the refrigerant and accumulates in the bottom reservoir or pool 9, accomplishing a relatively constant and equalized heat exchange between the refrigerant and the cooling water. This passage of the liquid over the refrigerant to produce heat exchange between the refrigerant and the cooling water is materially assisted by an extended surface support, preferably of metal of high conductivity, designated in the drawing as 30. This platform 30 has an opening where the ice rests or at any suitable point, so that the water melted from the ice can easily drain off and combine with the chilled water. In Fig. 1 this support takes the form of a corrugated metal platform, the top of which is a substantially flat surface. The surface which supports the refrigerant is formed preferably of a metal sheet which has been bent back upon itself forming channel members running longitudinally of the sheet, the upright portions of the channels positioned at an angle producing an extended or enlarged metal surface of high conductivity for transferring heat from the pool of liquid to the refrigerant, or the cooling effect of the refrigerant to the pool of liquid.
- In the modified type of construction shown in Fig. 2, the platform as shown at 30 in Fig. 1 would be replaced by a plain metal surface designated as 31, supported by a plurality of vertical upright perforated plates 32 or metal of high conductivity such as copper, non-corrosive steel or similar materials. In Fig. 4, the platform 31, such as that shown in Fig. 3, is supported by a plurality of pipes 33. These pipes may be provided with numerous radial or circumferential fins (not shown) to increase heat exchange surface. In both the modifications shown in Figs. 3 and 4, a lower plate of metal 34 is positioned below the supports.

It is to be understood that any suitable heat exchange surface may be employed without departing from the spirit of our invention.

Between the refrigerant support and the bottom of the refrigerating compartment is a heavy layer of insulating material as shown at 35 in all of the figures. The function of this insulation is to prevent loss of the cooling action of the refrigerant by transmission or conduction of heat through the casing. It is contemplated also that this insulation may be extended over the bottom of the spray chamber, although it is not so shown in the drawing. As the water in the reservoir in the compartment 5 is of somewhat higher temperature, there will be less conduction of heat through the casing than would be the case with the pool of liquid in the bottom of the refrigerating chamber.

In operation, the ice cake, or refrigerant, is placed upon the platform 30 and water is provided so as to submerge the greater part of the extended surface platform. The entire surface may be submerged to a depth of about two inches, so that the ice actually is contacted with the circulatory cooling water. The water is pumped from the reservoir 9 by means of the pump 18, a portion spraying into the spray chamber through spray nozzles 16 and 17, and a portion of the circulated water discharged from the spray 28 over the refrigerant 11. Simultaneously with the circulation of the water, air is introduced through the duct 12 and passes through the tortuous passage through the air conditioning chamber, being subjected therein to the conditioning effect of the water sprays. At the same time the water sprayed into the refrigerating chamber produces a heat exchange effect, carrying the cooling effect of the refrigerant to the pool of water maintained in the bottom of the device. The water sprayed into the refrigerating chamber as well as the ice itself, effects the cooling of the water in the reservoir principally due to the conductivity of the extended metal platform and passage of the sprayed water over the refrigerant.

The use of the insulated base between the enclosing floor or walls of the storage chamber provides a check to the conduction of heat to the ice from any other source than the water moved by the pump.

The water resulting from the melting of the ice is allowed to flow away from the base of the ice cakes by means of the openings in the platform, and excess water is discharged through the overflow pipe 10.

To those familiar with the cooling of water for air conditioning purposes when using ice, it is evident that one of the important features for successful operation is the ability to melt the ice at a rapid and constant rate.

Tests have shown that the melting rate of ice is materially increased by the use of an extended metal surface platform as compared with the direct contact between the ice and the reservoir water. The fact that the ice cakes must be supported and yet present a large exposed surface in contact with the water has in the past caused difficulties in the effective melting of the ice. This difficulty is to a great extent eliminated and done away with in the present air conditioning unit:

While we have described a unit, it is quite feasible to have the ice compartment and the spray compartment located at separated points. A plurality of ice and/or spray compartments may be used.

It will be understood that certain features, sub-combinations and operations are of utility and may be employed without reference to other features and sub-combinations. This is contemplated by and is within the scope of the appended claims. It is further obvious that many changes may be made in details, within the scope of the appended claims, without departing from the spirit of this invention. It is, therefore, to be understood that our invention is not to be limited to the specific details shown and described.

Having thus described our invention, we claim:

1. In an air conditioning device the combination with an ice receiving compartment, a separate spray compartment, an extended metal surface support for the ice, said surface partially immersed in a water reservoir in the ice compartment and means for circulating the water from the reservoir to the spray compartment.

2. In an air conditioning device the combination with an ice receiving compartment, a separate spray compartment, an extended metal surface support for the ice, said surface partially immersed in a water reservoir in the ice compartment, and means for circulating the water from the reservoir to the spray compartment and diverting a portion of the circulated water through the ice compartment.

3. In an air conditioning device the combination with an ice receiving compartment, a separate spray compartment, an extended metal surface support for the ice, said surface partially immersed in a water reservoir in the ice compartment, and means for withdrawing a controlled amount of water from the reservoir in the ice compartment and the spray compartment for circulation to the spray compartment.

4. In an air conditioning device the combination with an ice receiving compartment, a separate spray compartment, an extended metal surface support for the ice, insulation between the extended metal refrigerant support and the bottom of the ice compartment.

5. In a device of the character described,

the combination with a refrigerating compartment, a spray compartment, a water reservoir, a heat exchange member immersed in said water reservoir in said refrigerating compartment said member being formed with a surface adapted to support a cake of ice, and means for circulating the water from the reservoir to the spray compartment.

6. A device as claimed in claim 5 wherein the spray compartment is provided with an overflow outlet.

7. In an air conditioning device an ice receiving compartment, an extended surface in said compartment for supporting the ice, a separate spray compartment; and means for circulating water between said ice receiving compartment and said spray compartment.

8. In an air conditioning device the combination with an ice receiving compartment, a separate spray compartment, an extended metal surface support for the ice, said surface partially immersed in a water reservoir in the ice receiving compartment and means for circulating the water from the reservoir to the spray compartment, and insulation between the ice support and the bottom of the ice receiving compartment.

In testimony whereof, we affix our signatures.
